UNITED STATES PATENT OFFICE.

LOUIS W. G. FLYNT, OF NEWARK, NEW JERSEY.

SPARK PLUG.

Application filed November 3, 1921. Serial No. 512,438.

To all whom it may concern:

Be it known that I, LOUIS W. G. FLYNT, a subject of Great Britain, residing at Newark, in the county of Essex and State of

5 New Jersey, have invented new and useful Improvements in Spark Plugs, of which the following is a specification.

This invention has for one of its objects the provision of a gas tight joint between 10 the insulator and the metal body of the plug without the interposition of gaskets or packing material of any kind together with means for readily disassembling the insulator from the metal body to permit cleaning 15 or inspection.

A further object is the provision of an adjustable gap in the center electrode for the purpose of intensifying the igniting spark, in such a position as to permit visual 20 examination of the spark that jumps the gap together with means for preventing the intensifier spark from igniting inflammable gases or liquids that may come into contact with it, consisting of a transparent tube so 25 mounted in the insulator as to form a flame condenser.

These and other objects, which will later become apparent, are attained by the novel 30 design, construction and arrangement of parts hereinafter described and shown in the accompanying drawing, forming an essential part of this disclosure and in which:—

Figure 1 is a longitudinal sectional view 35 taken through the center of a spark plug made in accordance with the invention.

Figure 2 is a transverse sectional view taken on line 2—2 of Fig. 1.

Figure 3 is a similar sectional view taken 40 on the line 3—3 of Figure 1.

Referring to the drawing in detail, the numeral 10 designates the main cylindrical portion of the plug body, the same having a hexagonal upper portion 11 suited to receive 45 a wrench in securing the plug in operative position and a shoulder 12 at its lower end for seating purposes.

Below the shoulder 12 is a screw head 13 to engage with the support on which the 50 plug is mounted, the extreme end of the plug being relieved of threads as at 14.

Set rigidly in the level bottom of the plug is a conductor 15 having an angularly bent end 16 extending past the center of the 55 plug.

An axial cylindrical bore 17, at the bot-

tom of the body, merges into the smaller end of a conical recess 18, the larger, inverted base end of which is approximately in the plane of the upper end of the body 60 10, and above this recess the body is internally screw-threaded as at 19.

Fitting these threads is a clamp ring or annulus 20, its outer projecting end being formed into a hexagon head 20' receptive 65 of a wrench in making adjustment, its inner end being provided with a beveled counterbore the purpose of which shall presently appear.

The insulator is comprised of a conical 70 portion 21 having two or more slightly raised rings 22 and 22', preferably finished by grinding to accurately fit the conical recess 18, the lower ring being midway in the length of the cone which terminates at a 75 point above the cylindrical opening 17.

The upper contact ring 22 merges into a short cylindrical portion 23 necked as at 24 to a reduced diameter portion 25 which extends to a considerable height above the 80 annulus or clamp ring 20—20', through which it freely passes and terminates in a level top 26 having rounded corners as shown.

Disposed on the seat formed by the neck 85 24, is a metal ring 27, preferably of an alloy of aluminum having a high coefficient of expansion, the same being centered by the beveled contact surface of the clamp ring 20 when pressure is brought to bear 90 upon it in order that the pressure transferred to the insulator may be in a truly axial direction and thus result in a uniformly distributed pressure on the ground 95 surfaces of the steel body and the insulator where they contact to make a gas tight joint, as hereinbefore described. Pressure brought to bear on the metal ring 27 by the clamp ring 20 will circumferentially stress the clamp ring thus permitting its elasticity 100 to assist the metal ring 27, which has a higher expansion coefficient than the metal of which the plug body, 10, is made, to compensate for the expansion differences of the plug body and the insulator.

Formed in the insulator, at its lower end, is an axial passage 28 having a stepped reduced upper portion 29 into which leads a small central opening 30.

Tight fitted to this opening is the upper 110 element 31 of an insulated conductor having a conical point 32 at its upper end an en-

larged portion 33 which extends down through the passage 29 and 28 to a point adjacent the angularly turned conductor 16.

The element 31 may also be held in fixed 5 relation to the insulator by cement but preferably depends upon a frictional fit in it.

Freely fitted into a recess 34 formed in the upper portion of the insulator is a transparent tube 35, into which the conical point 32 of the conductor extends to about the center of the length of the tube and at which point a plurality of radial openings 36 are formed thru the insulator permitting it to be seen.

15 It is found in practice that intensifier sparks of the class described do not function properly if hermetically sealed and that ventilation is required. A freely exposed spark is liable to ignite stray inflammable 20 vapors or fluids, with consequent danger, but the surrounding of the sparking points with a loosely fitted transparent tube, such as 35, permits the necessary ventilation but prevents the escape of flame generated by the 25 spark on the inside of the tube by making its only passage to the outside thru narrow spaces whose walls are relatively cool so that they form a flame condenser.

Above the recess 34 the insulator is formed 30 with internal screw-threads suited to receive a metal plug 37 having a flanged head 38 through which passes an axial screw 39 having a conical point 40 registering with the point 32 of the lower conductor and adjustable therewith by the nut 41, on the upper surface of which may be disposed the usual type of electric connection (not shown) the same being secured by the knurled head nut 42 threaded adjustably on the extending 40 end of the screws 39.

In operation, the parts having been assembled as indicated and suitable electrical connections having been made respectively to the spark plug support and screw section 45 39 of the plug, current will pass through the conductors, the spark passing through the gap between the points 32 and 40 being visible to an operator.

It will be obvious that the intensity of 50 the spark may be measurably increased or diminished by proper adjustment of the distances between the points and that the operative sparking will take place as usual at the terminals 16 and 32.

55 It will also be apparent that a firm and

secure construction has been set forth, that the insulating element is well protected against damage, and further, that due to the air space surrounding the major portion of the lower conductor, it is less liable to collect 60 carbon than where a relatively short end is exposed.

Although the foregoing is descriptive of the preferred embodiment of the invention, it will be apparent that minor changes may 65 be made in its construction, without the exercise of invention or conflicting with the scope of the claims hereto appended.

Having thus described my invention, what I claim as new and desire to secure by 70 Letters Patent, is:—

1. A spark plug comprising a body having a conical cavity, an insulator, a raised upper and lower ring on said insulator accurately fitting the cavity, means for clamping said 75 insulator to said body, and a split, soft metal ring having a high coefficient of expansion interposed between said clamping means and said insulator.

2. A spark plug comprising a body having 80 a conical cavity, an insulator, a raised upper and lower ring on said insulator accurately fitting the cavity, means for clamping said insulator to said body, said means being provided with a beveled counter-bore, and 85 a split, aluminum ring having a high coefficient of expansion interposed between said beveled counter-bore and said insulator.

3. A spark plug comprising a body having 90 a conical cavity, an insulator, a raised upper and lower ring on said insulator accurately fitting the cavity, means for clamping said insulator to said body, and a split ring of an alloy of aluminum having a high coefficient of expansion interposed between said 95 clamping means and said insulator.

4. A spark plug comprising a body having a conical cavity, an insulator, raised rings on said insulator accurately fitting the cavity, means for clamping said insulator to said 100 body, a conductor fixed in said insulator, said conductor being unconfined for the greater portion of its length and a split aluminum ring having a high coefficient of expansion between said insulator and said 105 clamping means for producing a gas-tight joint.

This specification signed this eighteenth day of October, 1921.

LOUIS W. G. FLYNT.
